UNITED STATES PATENT OFFICE.

NAASON Z. BUTTERICK, OF JACKSONVILLE, FLORIDA.

DESIGN FOR A ROOFING ELEMENT.

61,363.

Specification for Design. Patented Aug. 15, 1922.

Application filed March 20, 1922. Serial No. 1,262. Term of patent 14 years.

To all whom it may concern:

Be it known that I, NAASON Z. BUTTERICK, a citizen of the United States, residing at Jacksonville, in the county of Duval and State of Florida, have invented a new, original, and ornamental Design for a Roofing Element, of which the following is a specification, reference being had to the accompanying drawings, forming a part thereof.

Figure 1 represents a plan view of a roofing element showing my new design;

Fig. 2 is a perspective view representing

one end of a roof covering consisting of roofing elements embodying my design; and

Fig. 3 is a plan view of a portion of a roof covering composed of roofing elements embodying my design showing the irregular wavy configuration simulating the corresponding portions of a thatched roof when the elements are laid in overlapping rows to constitute the roof covering.

I claim:

The ornamental design for a roofing element, as shown.

NAASON Z. BUTTERICK.
